(57) **CLAIM**

The ornamental design for a server device, as shown and described.

DESCRIPTION

All disclosure and subject matter, including all figures, of U.S. Design patent application Ser. No. 29/586,419 filed concurrently with this application on Dec. 2, 2016, are specifically incorporated in this application as if set forth fully herein.

FIG. 1 is a top front perspective view of a first embodiment of a server device showing our new design in a non-illuminated state;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a front perspective view of a second embodiment of a server device showing our new design in an illuminated state;

FIG. 9 is a front elevation view thereof;

FIG. 10 is a rear elevation view thereof;

FIG. 11 is a right-side elevation view thereof;

FIG. 12 is a left-side elevation view thereof;

FIG. 13 is a top plan view thereof; and,

FIG. 14 is a bottom plan view thereof.

The dashed broken lines in the drawings illustrate portions of the server device that form no part of the claimed design. The radiating lines represent the glowing visual effect created by light emanating from the array of light-emitting diodes and from around the circular button in the second embodiment of the server device shown in FIGS. 8-14.
